UNITED STATES PATENT OFFICE.

ARTHUR S. WELDY, OF TORONTO, ONTARIO, CANADA, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,116,771.

Specification of Letters Patent. Patented Nov. 10, 1914.

Application filed January 15, 1912. Serial No. 671,202.

To all whom it may concern:

Be it known that I, ARTHUR S. WELDY, a citizen of the United States, residing at the city of Toronto, in the county of York 5 and Province of Ontario, Dominion of Canada, have invented certain new and useful Improvements in and Relating to Filing Appliances, of which the following is a specification.

10 This invention relates to filing appliances that are adapted for receiving and removably supporting papers, slips, bills, records and documents in a manner permitting them to be easily and rapidly filed, inspected or 15 removed.

For the purpose of illustration, I have, in the accompanying drawings, shown and herein described one form of filing appliance embodying my invention.

20 Figure 1 is a side elevation of a filing appliance embodying my invention, the near side of the casing being broken away to facilitate the illustration of the holders or frames. Fig. 2 is a fragmentary side elevation of a series of holders, removed from the casing, certain of the holders being shown in section. Fig. 3 is a fragmentary bottom plan view of the holders. Fig. 4 is a perspective view of a connector or hinge 25 device for a holder, a portion of the adjacent holder being shown connected thereto. Fig. 30 5 is a side elevation of the connector, a portion of the adjacent holder being shown in section and connected thereto.

35 In the drawings, 1 indicates a casing which may be of any standard or preferred form of construction. Preferably, it comprises a main or desk section 1^a, and an upright section 1^c, having a back or rear wall 40 1^d. The main section 1^a is also provided with a top 1^e and suitable drawers or trays 1^f.

1^b indicates a base preferably arranged at the rear of and substantially in a plane co-45 incident with the top 1^e.

2 indicates blocks (only one being shown in the drawings) mounted on the base 1^b at or near its front edge. These blocks are formed with suitable bearings which removably receive and rotatably support the pivot or hinge pins of the frontmost holder of the series of holders 3, as will be presently described.

The holders 3 consist of a series of frames

which are preferably of uniform size. They 55 are adapted to be assembled normally in an approximately upright position face to face. Each frame preferably comprises a back 3^a formed from sheet metal, spacing strips 3^b extending in a direction longitudinally of 60 the frame, and paper engaging devices (not shown) secured to the opposite faces of the back and adapted for detachably supporting the papers or slips thereon in a well known manner. The strips 3^b are arranged along 65 the opposite longitudinal edges of the backs. Additional strips, each separated from adjoining strips, may be provided on each back 3^a between the side edges thereof, thus dividing the opposite faces of the back into a 70 series of pockets for the papers or slips. The strips also serve to impart rigidity to the backs. At its lower or hinged end, each back 3^a is extended and bent or doubled on a line 3^c flat upon itself against its adjacent 75 face, to form a doubled section 3^c, and then both layers of said back 3^a and folded over or doubled section 3^c are bent at right angles to the back along a line 3^d parallel to the fold 3^c to form a bottom plate or hinge 80 bar 3^e. This construction strengthens the back 3^a from end to end and also provides a strong rigid hinge bar therefor of simple form.

4 indicates a series of hinge connections 85 between the holders 3, serving to connect them together and permitting them to swing from the vertical to a horizontal position, and vice versa, either singly or in groups. While only one series of pivot connections 90 4 for the holders is shown, two series of connections are preferably provided, they being arranged near the opposite lower ends of the holders 3. The connections 4 consist of a series of connectors 4^a, one carried by 95 each holder, and hinge pins 4^b which pivotally connect adjacent connectors together.

Each connector 4^a comprises a section of metal 4^c which is cut on parallel lines extending inwardly from its opposite longitudinal edges to form a plate 4^d on which the hinge bar 3^e rests and a plurality of projecting members (preferably three) indicated at 4^e, 4^f, 4^g on one side thereof and a similar number of projecting members, indicated at 4^e, 4^f, 4^g, on the opposite side of said plate. As shown, the member 4^f is bent upwardly at substantially right angles

to the plate 4^d and in fitting engagement with the adjacent face of the back 3^a, while the members 4^e, 4^g are bent over or around the edge 3^e of the hinge bar 3^e and into engagement with the upper face thereof. As will be understood from the drawings, the members 4^e, 4^g coöperate with the member 4^f to rigidly secure the connector to the adjacent hinge bar 3^e. The members 4^e, 4^g, 10 are preferably of such length that their free ends will engage with that portion of the bent over section 3^e that lies against the back 3^a and hold said bent over section in close contact with the said back. Each of 15 the members 4^e, 4^g, and 4^f are bent or rolled into circular or loop form to provide bearings for the hinge pins 4^b. As will be clearly seen from the drawings, the bearing loop 4^f of one connector 4 fits between and 20 alines with the bearing loops 4^e, 4^g of the adjoining connector 4 to receive a pintle 4^b, which extends through said alined loops and pivotally connects said connectors together.

25 The hinge pins 4^b of the frontmost connectors 4 are arranged to rest in the bearing blocks 2 which form the front bearings for the front holder or as many holders as may be operated therewith at any one time. The 30 front holder being supported in the casing by the blocks 2, said holders when in the upright position will rest against the rear wall 1^d. A cushion 1^d may be interposed between the rear wall 1^d and the rear holder 35 to overcome stresses incident to the rearward swinging of the holders.

All the connectors 4, except the one for the rear holder 3, are of similar construction. The hinge pins between the holder 3 40 permit them to be detached one from another whereby their number can be increased or decreased at will. Since no bearing loop 4^f is necessary for the connector 4 of the rear holder 3, the plate thereof is bent over or 45 around the adjacent hinge bar 3^e, as shown at 4^a in Fig. 2.

5 indicates a guide member for guiding the rearmost holder 3 in its up and down movements, as the holders forward thereof 50 are operated. This member is supported by the rear wall 1^d. In the operative position of said guide (see dotted lines in Fig. 1) it may be inclined upwardly and forwardly in order that the upper edge of said 55 rear holder, and those holders which may be in the upright position, may be moved forwardly and rearwardly during their up and down movements. At or near its free end, the guide is preferably provided with a 60 catch or stop 5^a with which the rear holder 3 engages when elevated to its highest position. Through the engagement of the rear holder with the catch 5^a, said holder will be locked against operation to the horizontal 65 position.

The guide 5 is preferably pivoted to the rear wall at 5^b, whereby it will swing downwardly and rest on the free edges of the holders 3 when the latter are all returned to normal position. In this latter position 70 of the guide 5, its catch 5^a will lie in the path of the front holder and thus lock it and all of the holders against operation. However, to release the front holder 3 from the catch 5^a, the guide is pressed upwardly 75 slightly. If now the front holder is swung forwardly and downwardly, such operation will elevate the rear holder 3 which in turn will swing the guide upwardly against a stop 5^c.

The connections 4 between the holders 3 are of a character which tends to strengthen the hinge bars and backs. The connections also provide long bearings for the pivots, the effect of which is to keep the holders in perfect alinement, thus insuring ease of operation and durability. Again, the connections are of simple construction and consist of few parts, the connector plates being arranged for connection with the holders 90 without the use of nails, rivets or screws.

To those skilled in the art of making filing appliance of the class described, many alterations in construction and widely differing embodiments and applications 95 of my invention will suggest themselves, without departing from the spirit and scope thereof. My disclosures and the description herein are purely illustrative, and are not intended to be in any sense limiting.

What I claim is:

1. In a filing appliance, the combination of a support, a series of holders mounted on said support and each comprising a back having a horizontal hinge bar arranged at right angles thereto along its lower edge, and connections between the holders comprising a series of connectors and pins for pivotally connecting the holders together, each connector comprising a plate on which the adjacent hinge bar rests, a member bent over into engagement with the upper face of the hinge bar and securing the latter to the plate, and bearing loops on the opposite sides of said plate arranged to aline with the bearing loops of the plates of adjoining connectors.

2. A holder for a filing appliance comprising a back formed from sheet metal and bent flat upon itself against its face to form a doubled section and both layers of said doubled section being bent at right angles to the back to form a hinge bar.

3. The combination of a holder for a filing appliance comprising a back formed from sheet metal and bent flat upon itself against its face to form a doubled section and both layers of said doubled section being bent at right angles to the back to form a hinge bar, an angled plate on which the hinge bar

of the holder rests, having one member in fitting engagement with the back and another member clamped around and upon the hinge bar, and bearing loops carried by said 5 plate and adapted to aline with loops of the plate of an adjoining holder.

4. In a filing appliance, the combination of a support, a series of holders pivotally mounted on said support and arranged to be 10 assembled face to face, each holder comprising a sheet metal back, the said back being folded over on itself to form a doubled section and said doubled section being bent at right angles to the back to form a horizontal 15 hinge bar, and connections between the hinge bars permitting the holders to swing relative to each other.

5. A connector for connecting the holders of a filing appliance together comprising a 20 plate having two members projecting from either longitudinal edge thereof, one member on each side being bent laterally for engagement with a holder to secure the plate thereto and the remaining member on each 25 side being formed into a bearing loop and arranged to aline with a bearing loop of an adjoining connector to receive a pintle.

6. A connector for connecting the holders of a filing appliance together, comprising a 30 plate having a plurality of members projecting from its opposite longitudinal edges, each alternate member along either edge being arranged to engage the adjacent holder for securing the plate thereto and the 35 remaining members being rolled or formed into bearing loops and arranged to aline with the bearing loops of an adjoining connector to receive a pintle.

7. In a filing appliance, the combination 40 of a support, a series of holders mounted on said support and each comprising a back having a horizontal hinge bar arranged at right angles thereto along its lower edge, and connections between the holders comprising a series of connectors and pins for 45 pivotally connecting the holders together, each connector comprising a plate having a member on one side bent upwardly into engagement with the back, a member on its 50 opposite side bent over on said hinge bar and coöperating with the other member to secure the plate to the hinge bar, and bear-

ing loops on the opposite sides of said plate arranged to aline with the bearing loops of the plates of adjoining connectors. 55

8. In a filing appliance, the combination of a support, a series of holders mounted on said support and each comprising a sheet metal back, the said back being bent at right angles adjacent its lower edge to form a 60 hinge bar, and pivotal connections between the holders including connectors, one for each of said holders, the said connectors comprising a plate having three members projecting from its opposite longitudinal sides, 65 the middle member on one side of the plate being bent upwardly into engagement with the back and the opposite end members on the other side of the plate being bent over and upon the hinge bar and coöperating 70 with the said middle member to secure the plate thereto, and the remaining projecting members being formed into bearing loops and alining with the bearing loops of adjoining connectors. 75

9. In a filing appliance, the combination of a support, a series of holders mounted on said support and each comprising a sheet metal back, the said back being folded over on itself to form a doubled section and said 80 doubled section being bent at right angles to the back on a line parallel to the folded edge to form a hinge bar, and pivotal connections between the holders including connectors, one for each of said holders, the said 85 connectors comprising a plate having three members projecting from its opposite longitudinal sides, the middle member on one side of the plate being bent upwardly into engagement with the back and the opposite 90 end members on the other side of the plate being bent over and upon the hinge bar and coöperating with the said middle member to secure the plate thereto, and the remaining projecting members being formed into 95 bearing loops and alining with the bearing loops of adjoining connectors.

In testimony whereof I affix my signature in the presence of two witnesses.

ARTHUR S. WELDY.
